United States Patent Office

Des. 191,879
Patented Dec. 5, 1961

191,879

NECKBAND

Robert Speckert, Altadena, Calif.
(448 S. Hill St., Room 1302, Los Angeles 13, Calif.)

Filed June 22, 1959, Ser. No. 56,479

Term of patent 14 years

(Cl. D45—1)

FIG. 1.

FIG. 2.

FIG. 3.

FIG. 1 is a top perspective view of a neckband showing my new design;

FIG. 2 is a top plan view thereof; and,

FIG. 3 is a side elevational view thereof.

I claim:

The ornamental design for a neckband, as shown.
